BATTERYLESS IMPULSE TRANSMITTER

John E. Ostline, Chicago, Ill., assignor to Automatic Electric Laboratories, Inc., Chicago, Ill., a corporation of Delaware

Application May 9, 1946, Serial No. 668,449

3 Claims. (Cl. 179—90)

1

The present invention relates in general to impulse transmission and more particularly to impulse senders or calling devices of the type employed in telephone and like signalling systems.

Such calling devices most frequently take the form of a manually operable dial, and it has been customary in the past to provide each dial with impulse contacts arranged to generate impulses by momentarily interrupting the flow of battery current in a suitable signalling circuit. The need for a battery or some similar source of current connected to the signalling circuit to supply the current therein has made it impractical to employ a conventional dial in some situations, however (for instance, in sound powered telephone systems where no such source of current is readily available). Moreover, even where a source of direct current is at hand it frequently is undesirable to employ interrupted direct current signalling, due to the transmission characteristics of the signalling circuit or for other reasons.

It is the general object of the present invention, therefore, to provide a dial which will be suitable for use in the above situations, and which is simple and economical in construction and reliable in operation.

In keeping with this object one feature of the invention resides in the provision of a calling device which does not depend upon a battery or any similar auxiliary source of current for its ability to produce electrical impulses.

Another feature resides in the provision of a calling device capable of generating impulses which are better suited for transmission over signalling circuits of the kind frequently encountered in practice than are make-and-break direct current impulses. In particular, each impulse generated by the calling device of the invention comprises a transitory impulse of current.

Impulses of this character are obtained by providing interlinked magnetic and electrical circuits on the calling device, together with dial-controlled means for altering the linkage between the two in order to generate impulses in the electrical circuit. More specifically, the magnetic circuit is energized by a permanent magnet at the calling device, and mechanism is provided to alternately increase and decrease the reluctance of the magnetic circuit thereby to induce impulses into the associated electrical circuit. These impulses alternate in polarity, and according to another feature of the invention the impulses of one polarity are higher in voltage

2

and have a steeper wave front than do those of the opposite polarity.

Other objects and features of the invention will be made clear in the ensuing description of one embodiment thereof, reference being made to the accompanying drawings wherein:

Fig. 1 is a side elevation of the calling device according to the invention,

Fig. 2 is a rear elevation of the calling device,

Fig. 3 is a cross-sectional view taken along the line 3—3 of Fig. 1, showing the magnetic circuit of the calling device and the electrical coil associated therewith,

Fig. 4 is a view taken along line 4—4 of Fig. 2,

Fig. 5 is a schematic diagram of the calling device showing same connected to a suitable responding device, and

Fig. 6 shows a modified arrangement of the magnetic and electrical circuits in the calling device.

The calling device of the instant invention is substantially identical to that shown in Oberfell Patent No. 1,642,822, granted September 20, 1927, with the exception that the impulse cam 25 of the patent has been modified in shape and the associated impulse contacts have been replaced by an improved magneto or induced impulse generator which now will be described.

This generator comprises a permanent magnet 11 having secured to the opposite poles thereof a pair of pole pieces 12 and 13. Preferably the magnet is formed of a magnetic material having good retentivity, such as an alloy containing aluminum, nickel, and cobalt, while the pole pieces may be of soft iron or other suitable magnetic material. One of the pole pieces 13 is provided with an extension of reduced size over which a coil 14 is fitted; the end of the pole piece being bent over at 15 to hold the coil in place and also to form a pole face of enlarged area.

Adjacent the other pole piece 12 is a non-magnetic channel member 16 formed of brass or like material. A pair of nonmagnetic screws 17 extending through the channel member and pole pieces serve to clamp these members securely to magnet 11. This forms a rigid assembly which is attached to the body of the dial 18 by means of nonmagnetic clamping block 19 and a screw 21 extending therethrough into a tapped hole 50 in 18.

A portion of the channel 16 is cut away at one end, leaving a pair of forwardly projecting lugs 22 which carry a pivot pin 23; and a pivotal armature 24 is mounted on this pin. Made of soft iron or other suitable magnetic material, the

armature has a strip of nonmagnetic material 25 rigidly affixed thereto by screws 26. One end of this strip is arched away from the armature to provide a space between the strip and the armature for receiving pivot pin 23. The other end of the strip comprises an elongated finger which is adapted to cooperate with the impulse cam 27.

In order to dial a digit the finger hole plate 28 is rotated away from its normal position in the usual manner and permitted to restore. During the return of the plate to normal under the influence of its restoring spring 29, the dial gear train causes cam 27 to rotate in a counterclockwise direction at a uniform speed controlled by the governor 30, the number of revolutions of the cam being determined by the value of the digit dialled, as is described in the before-mentioned Obergfell patent. The cam is so shaped that during the first one half revolution thereof it causes the extended finger 25 to move armature 24 rather slowly away from its normal position against pole face 15. At the end of the first half revolution the set-off in the cam permits the armature to snap back against the pole face, it being understood that the armature is always pulled in this direction due to the attractive forces which are set up between the pole face and the armature by magnet 11. This mode of operation is repeated on the ensuing half revolutions of cam 27.

Each movement of the armature away from pole face 15 increases the reluctance of the magnetic circuit (shown dotted in Fig. 5), and the consequent change in flux linkage with coil 14 induces in the coil a transitory voltage impulse of a certain polarity; conversely each time the armature snaps back to normal from the position to which it has been displaced by cam 27, the reluctance of the magnetic circuit is reduced, producing a flux change which induces in the coil a transitory voltage impulse of the opposite polarity. The rate of change in flux linkage manifestly is considerably faster when the armature snaps back to normal than when the cam slowly moves the armature away from normal, and accordingly the impulse induced in the coil on the return movement of the armature has a somewhat higher voltage and a steeper wave front than the impulse induced during the armature's movement away from normal.

Considerable variation in the strength and waveform of the impulses generated by the dial may be obtained by altering the space relationship between the finger 25 and cam 27; this adjustment is easily made by loosening screw 21, moving the magnetic structure of the induced impulse generator slightly on the base 18 thereby to alter the position of 25 with respect to the cam, and then again tightening screw 21.

In use, the coil 14 may be connected over a line to any suitable form of impulse registering equipment, it being remembered that no auxiliary source of electrical current needs to be connected to the line to energize the registering equipment. For instance, as shown in Fig. 5, it may be connected over line 31 to a relay 32 which is so polarized that it will respond only to the impulses impressed upon the line when the armature snaps back to normal, contact 33 thus closing momentarily to transmit an impulse over conductor 34 responsive to each return of the armature 24 to normal.

Fig. 6 illustrates schematically a modified form of induced impulse generator for use in the dial,

wherein the magnetic circuit comprises a permanent magnet 35, two identical pole pieces 36 and 37, and an armature 38. The armature is free to turn above a pivot 39, but normally is held by a spring 41 in the position shown, so that the flux from magnet 35 follows the path indicated by solid arrows. When cam 27' rotates in a counterclockwise direction due to an operation of the finger hole plate of the dial, it slowly moves armature 38 against the tension of spring 41 to the position shown dotted and then permits the armature to snap back to normal under the influence of the spring, this process being repeated once for each half revolution of the cam.

On the slow movement of the armature to its dotted position the direction of flux through said armature reverses, as indicated by the dotted arrows, and this induces in a coil 42 which encircles the armature a transitory voltage impulse of a certain polarity; on the more rapid return of the armature to normal the flux through the armature again reverses, inducing in the coil a voltage impulse of the opposite polarity. Since the latter flux reversal takes place more quickly than the former, the consequent impulse induced in coil 42 is of a higher voltage and has a steeper wave front. The terminals of coil 42 may be connected over a line to any suitable responding device, as explained in connection with Fig. 5.

Having described the invention in detail, what I believe to be new and desire to have protected by Letters Patent is set forth in the appended claims.

What is claimed is:

1. In an impulse sender, a magnetic circuit including a pole piece and an armature, a coil encircling a branch of said magnetic circuit, a manually operable finger dial rotatable in accordance with the number of impulses to be transmitted, a spring means normally holding said armature in position against said pole piece and cam means controlled by the operation of the dial for moving the armature slowly away from its pole piece to induce a single weak impulse of current in one direction in said coil and cooperating with said spring means to cause said armature to restore rapidly to its original position to induce a single strong impulse of current in the opposite direction in said coil for each impulse to be transmitted.

2. An impulse sender having a rotatable dial manually rotated to different positions and having means for rotatably returning said dial after each manual operation, a magnetic circuit including a pole piece and an armature, a cam, coupling means for coupling said cam to said dial only on said return movement of said dial, said cam controlled by said coupling means on the return movement of the dial to move the armature slowly in a single movement in one direction away from its pole piece and spring means for quickly returning said armature to its pole piece in another single movement in the opposite direction for each movement of the dial through one position on said return movement, a coil wound around a portion of the magnetic circuit, a single weak impulse of current being induced into said coil by a slow change in reluctance in said magnetic circuit in response to each slow movement of said armature in said direction and a single strong impulse of current being induced in said coil by a quick change in reluctance in said magnetic circuit in response to each said quick return movement of said armature in said opposite direction for each position

through which the dial rotates on said return movement.

3. In an impulse sender, a magnetic circuit including pole pieces and an armature normally held against said pole pieces, a coil encircling said armature, a manually operable finger dial rotatable in accordance with the number of impulses to be transmitted, cam means controlled by the operation of the dial for moving said armature in a number of alternate slow and rapid movements of said armature dependent upon the number of impulses to be transmitted, one end of said armature being moved slowly away from one of said pole pieces to the other of said pole pieces and the other end of said armature being moved slowly away from said other pole piece by said cam means to said one pole piece to slowly reverse said magnetic circuit through said armature to thereby induce a weak impulse of current in one direction in said coil in response to each slow movement of said armature, a spring connected

to said armature for returning said armature to normal, said armature jointly controlled by said spring and said cam means for causing said armature to restore rapidly to normal to rapidly reverse said magnetic circuit back to normal to thereby induce a strong impulse of current in the other direction in said coil in response to each rapid movement of said armature.
